UNITED STATES PATENT OFFICE.

HARRY T. KOLP, OF ROYERSFORD, PENNSYLVANIA.

DESIGN FOR A PUZZLE-BOARD.

SPECIFICATION forming part of Design No. 32,838, dated June 12, 1900.

Application filed May 19, 1900. Serial No. 17,317. Term of patent 14 years.

To all whom it may concern:

Be it known that I, HARRY T. KOLP, a citizen of the United States, residing at Royersford, in the county of Montgomery and State of Pennsylvania, have invented and produced a new and original Design for a Puzzle-Board, of which the following is a specification.

This invention relates to a new and original design for a puzzle-board; and it has for its object to provide a design of this character that shall be both useful and ornamental.

The leading feature of the design resides in the board having a flat top surface provided thereon with a transversely-alined series of spaced approximately U-shaped pockets having their open sides disposed in the same direction, said flat top surface of the board being further provided at opposite or both sides of the plane of said pockets with a plurality of parallel rows of short straight projecting ribs, the ribs of each row being longitudinally alined and spaced apart and the ribs of one row being arranged in alternate or staggered relation with reference to the ribs of adjacent rows.

The minor feature of the design resides in the flat top surface of the board having certain of its short projecting ribs lying directly opposite the open sides of the pockets and the board being provided with an upstanding peripheral flange completely encircling the same.

In the drawings, Figure 1 is a perspective view of a puzzle-board embodying the herein-described design. Fig. 2 is a plan view thereof.

Referring to the drawings, the numeral 1 designates a board of a rectangular shape and provided with an upstanding peripheral flange 2, projecting above the plane of the flat top surface of the board. The said flat top surface of the board is provided thereon with a transversely - alined series of regularly-spaced approximately U-shaped pockets 3, whose walls project above the plane of said flat top surface and which have their open sides disposed in the same direction. At opposite or both sides of the plane of said transversely-alined series of pockets 3 the flat top surface of the board is further provided with a plurality of parallel rows of short straight ribs 4. The straight ribs 4 in each row are longitudinally alined and spaced apart, and the alined ribs of one row are also arranged in alternate or staggered relation with reference to the ribs of adjacent rows.

An additional feature of the design resides in the short ribs 4 in one row being disposed in positions to lie directly opposite the open sides of the pockets 3.

What is claimed is—

The design for a puzzle-board herein shown and described.

In testimony that I claim the foregoing as my own I have hereto affixed my signature in the presence of two witnesses.

HARRY T. KOLP.

Witnesses:

DAVID SPRINGER,
U. S. G. FIRKINER.
